UNITED STATES PATENT OFFICE.

EDWIN W. STONE, OF LONGMEADOW, MASSACHUSETTS, ASSIGNOR TO BIGELOW-HART-FORD CARPET COMPANY, OF THOMPSONVILLE, CONNECTICUT, A CORPORATION OF MASSACHUSETTS.

PILE-WIRE-POSITIONING HOOK.

Application filed June 26, 1928. Serial No. 288,343.

This invention relates to pile fabric looms and is more especially directed to pile wire positioning hooks which serve to retain the pile wires properly positioned during the 5 pile formation.

In weaving pile fabrics such as pile carpets and pile rugs it is now the practice to provide pile wires in the form of thin blades which are inserted in the shed and over 10 which certain of the pile forming warp threads are passed during the weaving operation. It is essential that the pile forming wires shall extend directly transversely of the fabric and shall retain their upright pile 15 forming position, but the strain upon the pile wires when the pile warp threads are passed about them is liable to cause the pile wires either to be turned downward from their proper upright position under the 20 strain of the pile forming warp, or, in some cases, to be deflected rearwardly near their central portions by the pull of the pile forming warp. These objectionable conditions are sometimes overcome by the use of pile 25 wire retainers or hooks which are so located that the shoulder of the hook portion of the retainer or hook will engage over the pile wire as it is moved to the fell of the cloth and hold it from deflection.

30 In weaving wide pile fabrics, the support for the pile wire retainers or hooks is liable to be deflected, especially in the backward direction, under the pull of the hooks engaged with the successive pile wires. This 35 is owing to the excessive strain that is placed upon the pile wires by the pile forming warps, which becomes especially manifested in certain figured pile fabrics, and one of the objects of the present invention is to provide means for compensating for any backward bend or deflection of the pile wire hook support and to accurately position the hook 40 for proper engagement with the pile wire last inserted and hold it in transverse relation to the warp threads.

45 The pile wire retainers or hooks should extend in parallelism with the warp threads and be held from lateral or deflecting movement, which would be liable to form a mark in the completed fabric, and another feature of the present invention therefore consists in so mounting the pile wire retainers or hooks that they shall maintain their proper 50 backwardly extending position and be prevented from lateral movement, so that any

markings on the cloth that might otherwise occur are prevented.

During the continued use of the pile wire retainers or hooks, the shouldered or hooked portion of the retainer is liable to become 60 worn in part and the present invention provides means whereby such hooked or shouldered portion may be ground or filed into proper shape and then brought to its proper pile wire retaining position by means be- 65 tween the pile wire hook and its support.

The invention and new features thereof and novel combination of parts will be better understood from the following description and the accompanying drawings of one good 70 form thereof.

In the drawings:

Fig. 1 is a perspective view of certain portions of a loom at the front thereof, parts being broken away, and containing the present invention;

Fig. 2 is a sectional perspective of an eccentric or bushing that may be utilized in positioning the pile wire hook with which it is associated;

Fig. 3 is a fore-and-aft section of the front portion of a loom containing the present invention, only so much of the loom itself being illustrated as to make clear the relation of the present invention therewith;

Fig. 4 is an enlarged section through the pile wire hook support, some of the parts being broken away; and

Fig. 5 is an underside view of the pile wire hook, showing more particularly the 90 guiding means for retaining the hook in its proper backwardly extending position.

In the present instance, the invention is shown as employed in connection with a pile fabric loom for weaving carpets, rugs and 95 the like, in which the pile loops are cut, but it is to be understood that the invention is not restricted in this respect and that features thereof are equally applicable and advantageous in weaving any of the usual pile 100 fabrics. Also, the loom in the present instance is shown as the "wide type" for the production of pile carpets and rugs of unusual width, but again it is to be understood that the present invention is not limited 105 thereto although its advantages are well manifested when employed as described.

The loom frame 1 may be of any usual construction adapted for the weaving of wide fabrics, and at the front thereof there 110

is a spike or sand roll 2 which extends transversely of the loom and over which the pile fabric *a* passes as it is progressively woven.

The lay 3 may be of usual construction 5 and, as shown, is carried by the lay swords 4, as usual. Mounted upon the lay is the reed 5 which extends between the base of the reed and the cap or hand rail 6, the reed being formed as usual with dents in 10 separated relation for the passage of the warp threads *b*.

Rising from the front portion of the loom at each side thereof are the stands 7 which may be secured to the loom in any appropriate manner, as by the bolts 8, and such stands form the bearings for the transversely 15 extending pile wire hook support 9.

The pile wire hook support 9, as indicated in Figs. 1, 3 and 4, is preferably of circular 20 cross-section and may be variously contrived, but, as illustrated, it is shown as of tubular form, which imparts the necessary strength to the pile wire hook support without undue weight. In certain aspects of the 25 invention, the pile wire hook support 9 may be differently contrived, but the circular cross-sectional construction is preferred.

In wide looms for weaving pile fabrics it 30 is desirable to provide a number of pile wire hooks or retainers distributed at intervals transversely of the loom, but as such pile wire hooks or retainers may all be of the same character or construction, a description of one will be sufficient for all. As 35 shown in the illustration of Fig. 1, four pile wire hooks or retainers are employed, but of course the number may be varied to suit the conditions of use.

Mounted upon the pile wire hook support 40 9 are a series of eccentrics 10 each of which may have a saw-cut 11 and be provided on its outer edge with a flange 12, the construction being such that the eccentric itself 45 may be turned to different positions on the pile wire hook support 9 and may also be moved transversely of the loom to different transverse positions thereon.

Each of the eccentrics 10, of which there 50 may be any number, has mounted thereon the clamping member which affords a support for the pile wire hook. In the present instance of the invention the clamping member comprises the two parts 13 and 14 which 55 may be clamped upon the associated eccentric 10 by means of the bolts 15 which extend through and are threaded in ears 16 extending from the clamp members, the construction being such that when the members 13 and 14 are clamped upon the eccentric 10, 60 the latter is held from both rotative and lateral movement relative to the pile wire hook support 9; but should the clamp members 13 and 14 be loosened by manipulation of the bolts 15, the eccentric may be moved 65 longitudinally of the pile wire hook support

9 and may be rotated relatively thereto for a purpose that will more fully appear. The champing members and eccentric constitute one good form of pile wire hook mounting between the support 9 and pile wire hook.

Extending backwardly from the clamp member 14 is the arm 17 having its rear end portion bifurcated, as at 18, and pivotally connected to the arm 17 at 19 in the bifurcated portion 18 is the pile wire positioning hook or retainer 20. The pile wire hook or retainer extends rearwardly from its pivotal mounting 19 and its rear end portion 21 passes between the adjoining dents 70 of the reed 5. The pile wire positioning hook has a shoulder or hook portion 22, the purpose of which is to engage back of the last inserted pile wire 23 when it is placed in the pile forming shed.

Frontward of the pivotal connection 19 85 between the pile wire hook and the arm 17, the pile wire hook is extended to provide an arm 24 which has a portion 25 in the bifurcation 18 of the arm 17, with the result that any tendency to lateral movement of 90 the pile wire hook is restrained.

It is desirable that the shoulder or hook portion 22 of the pile wire hook shall engage the upper rear portion of each successive pile wire as it is inserted in the formation of the pile loops, and in order that the proper vertical relation between the shoulder 22 and the pile wire may be secured, means are provided between the clamp or arm 17 thereof and the forwardly extending portion 100 24 of the pile wire hook to vary the vertical position of the hook or shoulder 22.

In the present instance of the invention, the forwardly extending arm 24 of the pile wire hook is provided with a recess 26 which 105 may be appropriately formed as of conical shape for engagement by the lower conical end of the adjusting screw 27 held locked in its adjusted position by the nut 28, the result being that while the pile wire hook 110 may be adjusted in a vertical plane about its pivotal support 19 and be retained from lateral displacement by the bifurcation 18 engaged with the projection 25 of the hook, the lower conical end of the adjusting screw 115 27 also contributes to the maintenance of the pile wire in its backwardly extending position without lateral displacement.

Since the pile wire hook is pivotally connected to its support it readily permits the 120 last inserted pile wire to be moved frontwardly into position frontward of the shoulder or hook 22 by slight upward movement of the pile wire hook, and to return the hook to proper engagement with the pile 125 wire the present invention contemplates the provision of yielding means acting in a vertical direction upon the pile wire hook.

In the present instance of the invention, such means comprises a resilient or spring 130

arm 29, one end of which may be secured by the screws 30 to the arm 17, and have its backwardly extending portion resting on the top of the pile wire hook, as indicated more 5 clearly in Figs. 1, 3 and 4.

The rear end portion of the spring arm 29 is provided with the side embracing members 31 which include between them the rearwardly extending portion of the pile wire hook, 10 the construction being such that the embracing members 31 or lugs serve not only to maintain the spring arm 29 in proper relation with the hook but contribute further to the prevention of lateral displacement of the 15 hook itself, thereby cooperating with the bifurcation 18 and adjusting screw 27 to maintain the pile wire hook in its rearwardly extending position without lateral displacement, which would be liable to mark the 20 cloth should such displacement take place.

Since the rearwardly extending portion 21 of the pile wire hook passes between the dents of the reed, and since the lay swings about the pivotal support near the lower portion 25 of the loom, it is desirable to provide the rearwardly extending portion 21 of the hook with a recess 32 to permit the cap 6 to take its circular course about the pivotal mounting of the lay without striking the 30 rear portion of the pile wire hook, a condition indicated by full and dotted lines in Fig. 3.

As hereinbefore stated, the rearward pull upon the pile wire hook support 9 has a 35 tendency to deflect the support rearwardly and this is especially manifested in a wide loom such as herein shown and described. The present invention, however, affords a ready means for meeting this condition by 40 mounting the pile wire hooks upon the pile wire hook support 9 for adjustment frontwardly and rearwardly, as, for instance, by the eccentrics 10. To readily accomplish the adjustment where the eccentrics are employed 45 and to compensate for any rearward deflection of the pile wire hook support 9, it is only necessary to manipulate the clamping bolts 15, loosen the clamp members upon the eccentric, turn the eccentric to its proper 50 or desired position and then set up the clamp members as before.

The shoulder 22 or hook which engages the pile wire may become worn and require grinding or filing, which of course places its 55 active hooked surface further back, but by the present invention and the adjustment afforded by the eccentrics, such grinding or filing of the hook or shoulder may be effected and then compensation made therefor by a 60 slight turning movement of the eccentric associated with the hook, in a manner hereinbefore stated.

Similarly, it may be desirable at times to 65 change the lateral position of one or more pile wire hooks, and in accordance with the

present invention this may be effected by manipulation of the bolts 15 of the clamp members to loosen the eccentric and thereby permit it to be moved laterally of the pile wire hook support 9 or transversely of the 70 loom, and when the clamps are set up by the bolts 15 the yielding character of the eccentric 10 furnished by the saw-cut 11 therein, firmly and effectively secures the pile wire hook in its desired position. 75

The guidance of the pile wire hook or hooks to maintain them in their desired rearwardly extending position and from lateral displacement calculated to mark the cloth, may be variously contrived from the particular means herein shown and described but the mounting of the pile wire hook, the bifurcation 18 and projection 25, the adjusting bolt 27 and the side embracing portions 31 of the spring 29, all contribute to insure 80 the desired unchanging position of the pile wire hook, and while some of these features may not be necessary in all cases, the present invention nevertheless provides means for maintaining the pile wire hooks in their 85 proper rearwardly extending position without liability of lateral displacement which might injuriously affect the cloth. 90

What is claimed is:

1. In a pile fabric loom the combination 95 of a pile wire hook support extending transversely of the loom, a pile wire hook carried by said support and constructed to engage the last inserted pile wire to retain it in position during the pile loop formation, and an eccentric mounted for rotative adjustment between the support and the pile wire hook that the hook may be positioned for engagement with the pile wires. 100

2. In a pile fabric loom the combination 105 of a pile wire hook support of circular cross-section extending transversely of the loom, a pile wire hook carried by said support and constructed to engage the last inserted pile wire to retain it in position during the pile loop formation, and an eccentric mounted for rotative adjustment between the support and the pile wire hook that the hook may be positioned for engagement with the pile wires. 110

3. In a pile fabric loom, the combination 115 of a pile wire hook, a pile wire hook support, a pile wire hook mounting between the support and pile wire hook including an eccentric rotatable relative to the pile wire 120 hook to properly position the latter for engagement with the pile wires.

4. In a pile fabric loom, the combination 125 of a hook support of circular cross-section, an eccentric mounted on the support, the eccentric and support being relatively rotatable, and a pile wire hook mounted on the eccentric.

5. In a pile fabric loom, the combination 130 of a hook support of circular cross-section

extending transversely of the loom, an eccentric mounted for rotative movement on the hook support, a clamp member mounted on the eccentric, and a pile wire hook carried by the clamp member and adapted to be moved into proper position relative to the hook support by rotative movement of the eccentric that the hook may engage the last inserted pile wire.

10 6. In a pile fabric loom, the combination of a support extending transversely of the loom, a clamp member secured to said support, a split eccentric between the support and clamp member that the latter may secure the eccentric in adjusted position and a pile wire hook pivotally connected to the clamp member and extending rearwardly therefrom.

7. In a pile fabric loom, the combination 20 of a transversely extending tubular support at the front of the loom, a clamp member embracing said tubular support and having a rearwardly extending arm, means for clamping the clamping member about said tubular support in different positions thereon, a pile wire hook pivotally connected with the arm, and a pile wire hook guide engaging the pile wire hook for maintaining the hook in the same vertical plane between adjacent warp threads at the fell of the cloth.

8. In a pile fabric loom, the combination 30 of a tubular support extending transversely of the loom, a clamp member carried by the support and provided with a rearwardly extending arm, means interposed between the tubular support and clamp member for adjusting the clamp member towards and from the front of the loom on the tubular support and a pile wire hook pivotally mounted on 40 said arm.

9. In a pile fabric loom, the combination of a support extending transversely of the loom, a pile wire hook mounted on the support for adjustment to different positions transversely of the loom, an eccentric for 45 moving the hook to different positions to and from the front of the loom that it may engage the last inserted pile wire, and guiding devices for maintaining the hook in a fixed vertical plane that the hook may not mark 50 the fabric being woven.

10. In a pile fabric loom, the combination of a transversely extending support, a member mounted thereon and having a rearwardly extending arm provided with a pile wire hook guiding portion, a pile wire hook pivotally connected to the rearwardly extending arm and having a part cooperating with the guiding portion of the arm to maintain the hook from lateral displacement, and a 60 second guide engaging the hook back of its pivotal connection with the rearwardly extending arm.

11. In a pile fabric loom, the combination of a transversely extending support, a member mounted thereon and having a rearwardly extending arm provided with a pile wire hook guiding portion, a pile wire hook pivotally connected to the rearwardly extending arm and having a part cooperating with 65 the guiding portion of the arm to maintain the hook from lateral displacement, and a second guide constituted as a resilient member engaging the hook and normally acting to yieldingly hold the hook in position to 70 cooperate with the pile wires.

In testimony whereof, I have signed my name to this specification.

EDWIN W. STONE.
